DESIGN FOR ICE CREAM, POP CORN, CANDY, OR CAKE.

61,293.

Specification for Design.

Patented Aug. 1, 1922.

Application filed March 1, 1922. Serial No. 959. Term of patent 7 years.

To all whom it may concern:

Be it known that I, WILLIAM H. FRANCIS, a citizen of the United States, residing at Southington, in the county of Hartford and State of Connecticut, have invented a new, original, and ornamental Design for Ice Cream, Pop Corn, Candy, or Cake, of which the following is a specification, reference being had to the accompanying drawing, forming part thereof.

I claim:

The ornamental design for ice cream, pop corn, candy, or cake, as shown.

WILLIAM H. FRANCIS.

Witnesses:

HARRY H. MERRELL,

KATHERINE R. DONLAN.
